DESIGN FOR A HOBBYHORSE OR SIMILAR ARTICLE

Robert F. Brown, Greeneville, Tenn.

Application September 28, 1944, Serial No. 115,506

Term of patent 14 years

(Cl. D34—15)

To all whom it may concern:

Be it known that I, Robert F. Brown, a citizen of the United States, residing at Greeneville, in the county of Greene and State of Tennessee, having invented a new, original, and ornamental Design for Hobby-horses or Similar Articles, of which the following is a specification, reference being had to the accompanying drawing, forming part thereof. The figure is a side view, slightly in perspective of a hobby-horse, showing my new design.

I claim:

The ornamental design for a hobby-horse or similar article, as shown.

ROBERT F. BROWN.
